UNITED STATES PATENT OFFICE.

GEORGE A. KUNTZ, OF DES MOINES, IOWA.

SAFETY CRANKING DEVICE FOR ENGINES.

1,176,908.

Specification of Letters Patent. Patented Mar. 28, 1916.

Application filed March 12, 1915. Serial No. 13,997.

To all whom it may concern:

Be it known that I, GEORGE A. KUNTZ, a citizen of the United States, residing at Des Moines, in the county of Polk and State of Iowa, have invented new and useful Improvements in Safety Cranking Devices for Engines, of which the following is a specification.

This invention relates to safety cranking devices for engines the object in view being to provide a device capable of being attached to an automobile or motor car for the purpose of eliminating the danger to the operator in cranking an internal combustion engine with the ordinary hand crank which has been in use for so many years.

More specifically stated, the object of the invention is to provide a device which is controlled by the usual spark lead lever and which is arranged to be interposed between the cranking shaft and the shaft of the engine so that it is impossible to bring said shafts into coöperative relation to each other while the commutator or timer is in a position to advance the spark of the ignition apparatus. Consequently, the operator, before he is enabled to crank the engine, is first required to move the commutator to spark retarding position, under which condition there is no liability of the engine to "kick back" or start revolving in the wrong direction, the same frequently resulting in the arm of the operator being broken or otherwise seriously injured.

With the above and other objects in view, the invention consists in the novel construction, combination and arrangement of parts, as herein described, illustrated and claimed.

In the accompanying drawings: Figure 1 is a front elevation showing the device of this invention applied to an internal combustion engine with the shield interposed between the clutch elements of the cranking shaft and engine shaft. Fig. 2 is a similar view showing the position of the shield when the commutator has been moved to spark retarding position. Fig. 3 is a plan view of the mechanism, showing the relation of the shield to the engine shaft and cranking shaft.

The mechanism of this invention comprises a comparatively small number of parts, A designating the shield operating arm, C the shield, D the shield retaining spring, and E the shield supporting bracket.

F designates the ordinary oscillatory com-

mutator or timer provided with the operating arm *f* from which a rod or other connection *g* extends to a rock shaft leading along the steering column of an automobile and having attached thereto what is termed the spark lead lever operating in conjunction with the usual quadrant, the means just described enabling the commutator F to be oscillated in one direction or the other for the purpose of retarding or advancing the spark.

The shield actuating arm A comprises a substantially annular or circular end portion *a* of proper size to fit around the hub *f'* of the commutator or timer F, the said annular portion of the arm being clamped tightly around the hub *f'* by means of a clamping screw or bolt *f*². The end portion or extremity of the arm A is offset at substantially a right angle to form an operating tongue *h* which extends through an opening *h'* in the shield C the purpose of which will presently appear. The main body of the shield C is substantially in the form of a disk of sufficient size to be interposed between the clutch face or element at the inner end of the cranking shaft H and the complementary clutch element H' on the adjacent extremity of the engine shaft thereby preventing said clutch elements from being brought into coöperative relation to each other. The shield C is pivotally mounted on a stub shaft *i* carried by an L-shaped supporting arm or bracket I bolted or otherwise secured at *i'* to the frame or body of the engine. The supporting bracket is provided with an offstanding extension *k* to which is attached one extremity of a contractile spring D the other extremity of which is connected at *m* to the shield C at such a point that when the shield is shifted to the upper limit of its movement, the spring serves to hold the shield temporarily at such point while the operator is cranking the engine and when the shield is moved to its position between the clutch elements, said spring serves to temporarily and yieldingly hold the shield in the last named position. It will be observed that the shield operating arm A is adjustable relatively to and around the hub of the commutator or timer F so that the relative range of movement of said parts may be varied in accordance with the requirement in each case.

The spring and the arm A are adjusted so as to throw the shield C downwardly be-

tween the starting crank and the engine shaft just before the spark lead lever reaches a point where the commutator is set to advance the spark, thus making it necessary 5 for the operator to retard the spark before the starting crank may be operated in conjunction with the engine shaft. The opening h' allows the spark lead lever to be moved from a full retarding position to a 10 fully advanced position on the quadrant without interfering in any way with the other parts of the motor. Therefore, if for any reason, the spark is left too far advanced, the starting crank cannot be engaged 15 with the engine shaft until the spark is retarded.

What I claim is:—

1. In a safety cranking device for engines, the combination with the cranking shaft and 20 the engine shaft having coacting clutch elements, of a shield movable between said clutch elements, a commutator, means connecting said shield and commutator operating to interpose the shield between said 25 clutch elements when the commutator is moved to advance the spark, and to displace

the shield from such position when the commutator is moved to spark retarding position, and a spring attached to said shield and acting to yieldingly hold the same at 20 either limit of its throw.

2. In a safety cranking device for engines, the combination with the cranking shaft and the engine shaft having coacting clutch elements, of a shield movable between said 35 clutch elements, a commutator, and a shield operating arm on the latter positively engaging said shield and operating to interpose the shield between said clutch elements when the commutator is moved to advance 40 the spark, and to displace the shield from such position when the commutator is moved to spark retarding position, said arm being adjustable on the commutator to admit of a variation in the relative range of movement 45 of the shield and commutator.

In testimony whereof I affix my signature in presence of two witnesses.

GEORGE A. KUNTZ.
